UNITED STATES PATENT OFFICE.

JOHN A. BOYD AND PATRICK ROGAN, OF ST. MARYS, PENNSYLVANIA.

CLAY-PRODUCTS-SURFACING MECHANISM.

1,193,663.

Specification of Letters Patent. Patented Aug. 8, 1916.

Application filed September 30, 1915. Serial No. 53,414.

To all whom it may concern:

Be it known that we, JOHN A. BOYD and PATRICK ROGAN, citizens of the United States, residing at St. Marys, in the county of Elk and State of Pennsylvania, have 5 jointly invented certain new and useful Improvements in Clay-Products-Surfacing Mechanism; and we do hereby declare the following to be a full, clear, and exact description of the invention, such as will enable others skilled in the art to which it appertains to make and use the same, reference being had to the accompanying drawings, and to the letters of reference marked 10 thereon, forming part of this specification.

This invention relates to the manufacture of clay products, and especially to building materials, such as brick and wall tile.

The object of this invention is to provide 20 mechanism whereby the surface of the brick or tile which is to constitute the weather face thereof, may be given a rough texture which resembles the roughness of Astrakahn cloth, or Persian lamb fur. This result we 25 accomplish by providing scraper-like mechanism, which operates upon the column of clay as it emerges from the forming die of the auger machine and caused the surface thereof to roll up under the edge of the 30 scraper in small irregular rolls, which project in small points and knobs, beyond the body of the column, so that when the brick or tile so treated, are dried and burned, they will have a rough weather face closely resembling 35 Astrakahn cloth or Persian lamb fur, which, when laid in a wall, has a very artistic and pleasing effect.

The features of our invention are herein-after fully set forth and pointed out, and 40 are illustrated in the accompanying drawings, in which:—

Figure 1, is a side elevation of a portion of an auger machine with a brick column forming-die thereon, and our surfacing mechanism in position thereon. Fig. 2, is a 45 front end view of the same. Fig. 3, is a like view of a portion of an auger machine with a tile-forming die thereon, and our surfacing mechanism in position thereon. Fig. 50 4, is a front end view of the same. Fig. 5, is an enlarged diagrammatic view of our surfacing mechanism. Fig. 6, is a view of a portion of a tile-block, illustrating the 55 general effect of the weather surface, produced by means of our invention.

In these drawings A, indicates a portion

of an auger machine, A', and A², indicates the forming dies thereon. The die A', in Figs. 1 and 2, is provided with the usual rectangular opening for forming a column 60 of clay (see Fig. 1) from which bricks are cut in the usual manner.

The die A², (see Fig. 3) is provided with the usual opening of suitable size and shape to form the outside walls of a column of 65 clay, from which blocks of the desired length may be cut, in the usual manner. This die A², is also provided with the usual core mechanism a and a' which is secured upon the inner side of the die in the usual manner. All of these parts are of usual and ordinary construction, and form no part of 70 our invention.

Adjacent to the front of the dies A or A', we position scraper mechanism which is 75 adapted to operate upon one or more of the exterior surfaces of the columns of clay C or C', as it emerges from the die. The form of scraper preferred by us, and the manner of mounting is as follows, viz:—Upon the 80 front of the dies A' and A², we mount a shaft B, in suitable brackets B', which are secured upon said dies by means of tap bolts, or in any other manner which may be preferred. That portion of the shaft B, between the brackets B' B', is preferably 85 square in cross section, as shown in Figs. 3 and 5, and upon the flat sides of this square portion of said shaft we secure scraper-blades b b b b, which are sufficiently wide 90 to engage the surface of the clay column C or C', as it moves forward out of the dies A or A². Upon the shaft B, is a pulley D, (see Figs. 2 and 4) upon which a belt D', leading from a suitable source of power, 95 operates to cause the shaft and scraper-blades to rotate.

In case it is desired to operate on two surfaces, as shown in Figs. 3 and 4, we mount another shaft B², in suitable brackets 100 secured upon the die, upon which we secure scraper-blades b, as described in reference to the shaft B, which shaft B², is driven from the shaft B, by means of miter gears b'. In practice the column of clay moves 105 at about one thousand feet an hour, and we have found that the best results are obtained by causing the scraper-blades to revolve at from two-hundred to three-hundred revolutions a minute; but it may be found 110 that desirable results can be obtained by revolving the scrapers at different speeds,

When the scrapers are operated as above described, the surface of the clay is caused to roll up into innumerable and irregular projections E, as shown in Fig. 5, which are 5 illustrated in perspective view in Fig. 6.

While we have shown and described one form of scraper mechanism suitable for practising our invention, it is obvious that many other forms of mechanism may be 10 employed therefor, without departing from the spirit of our invention.

It is also obvious that instead of locating the surfacing mechanism of our invention adjacent to the die, it may be located at 15 some distance from said die, and the column or blocks cut therefrom, carried to the same, without departing from the spirit of our invention. Therefore we do not desire to be limited to the exact mechanism shown 20 and described, but,

Having shown and described our invention so as to enable others to construct and utilize the same, what we claim as new and desire to secure by Letters-Patent, is:

25 1. In a device of the class described, a shaft, straight blades thereon, means to support the same in engagement with a column

of clay, and means to rotate said shaft, whereby the surface of the column will be caused to break into irregular upturned projections, substantially as set forth. 30

2. In a device of the class described, a clay forming die, means to force a continuously moving column of clay through said die, a shaft, supported adjacent to said die; 35 straight blades thereon adapted to effect a trailing engagement with said column of clay, and means to cause said shaft and blades to rotate, substantially as described.

3. In a device of the class described, a 40 clay forcing mechanism adapted to eject a continuously moving column of clay, a square shaft mounted transversely to said column, straight scraper blades secured upon the flat sides of said shaft and engaging 45 said column with a trailing engagement, and means to cause said shaft and blades to rotate, whereby the surface of said column is caused to break into upturned irregular projections, substantially as described. 50

In testimony whereof I affix my signature.

JOHN A. BOYD
PATRICK ROGAN
